DESIGN FOR A PERFUME RECEPTACLE
AND APPLICATOR

Louis L. Patterson, Los Angeles, Calif.

Application August 30, 1946, Serial No. 132,983

Term of patent 14 years

(Cl. D86—10)

To all whom it may concern:

Be it known that I, Louis L. Patterson, a citizen of the United States, residing at Los Angeles, in the county of Los Angeles and State of California, have invented a new, original, and ornamental Design for a Perfume Receptacle and Applicator, of which the following is a specification, reference being had to the accompanying drawing, forming part thereof.

The figure is a perspective view of a perfume receptacle and applicator, showing my new design.

I claim:

The ornamental design for a perfume receptacle and applicator, substantially as shown.

LOUIS L. PATTERSON.
